ALBERT H. DE VOE, OF WESTFIELD, NEW JERSEY, ASSIGNOR TO THE SINGER MANUFACTURING COMPANY, A CORPORATION OF NEW JERSEY.

OVERSEAMING-STITCH-FORMING MECHANISM.

1,162,987.

Specification of Letters Patent.

Patented Dec. 7, 1915.

Application filed May 2, 1912. Serial No. 694,657.

To all whom it may concern:

Be it known that I, ALBERT H. DE VOE, a citizen of the United States, residing at Westfield, in the county of Union and State 5 of New Jersey, have invented certain new and useful Improvements in Overseaming-Stitch-Forming Mechanisms, of which the following is a specification, reference being had therein to the accompanying drawings.

10 This invention relates to an improvement in overseaming stitch-forming mechanism, and it is designed more particularly for stitching together and serging the superposed marginal portions of the uppers and 15 soles of Japanese footwear known as "tabis".

The invention has for its object to provide a simple and effective mechanism of this class which shall be strong and durable and in which the needle-jogging means is so 20 arranged as to prevent obstructing the operator's view of the work.

It has for its further object to provide mechanism for producing a strong seam for uniting the soles and uppers of the tabis and 25 for effectively confining their raw edges to prevent raveling.

As preferably constructed, the machine is provided with a rectilinearly reciprocating sectional tubular needle-bar carrying a fixed 30 and a laterally movable needle and having a fixed bearing embraced by the spaced members of a yoked rocking frame journaled upon said needle-bar and connected with suitable means for imparting rocking movements thereto. Journaled within the needle-carrying section of the needle-bar and 35 having a bearing in the other section thereof is a crank-rod having at its lower end a crank operatively connected with the carrier 40 for the laterally movable needle and at its upper end a lateral arm fixed thereon intermediate the adjacent ends of the needle-bar sections and having a pivotal and sliding connection with said rocking frame, where- 45 by the jogging movements are imparted to the laterally movable needle by a connection with the rocking frame passing through the needle-bar so as to reduce to the smallest bulk possible the parts carried by the needle- 50 bar nearest the work. The jogging needle-carrier is preferably in the form of a slide-block mounted in a transverse slideway of the needle-bar and having a lateral arm formed with a stud embraced by the eyed 55 end of a slide-pin entering a radial socket in the crank at the lower end of said crank-rod.

In the preferred form of the improvement, the loop-taking devices comprise rotary hooks having stationary thread-cases journaled therein and mounted upon upright shafts carrying bevel pinions meshing with similar independently mounted pinions upon an intermediate shaft connected with and adapted to rotate at double the speed of the needle-bar actuating shaft, thereby imparting two rotations of the loop-takers to each reciprocation of their respective needles. One of the loop-taker shafts is mounted in a fixed bearing bracket and the other upon a jogging frame having a fulcrum 70 transverse to said loop-taker shafts and to the intermediate shaft and provided with a lateral arm connected by a pivotal pin with a block apertured to embrace an actuating eccentric loosely mounted upon said intermediate shaft and rotating at one-half the speed of the needle-driving shaft.

The jogging frame carries a holding arm adapted to engage a portion of the thread-case of the jogging loop-taker to restrain it 80 from rotation therewith and in this arm is secured a thread-controlling finger adapted to engage the lower thread of the jogging loop-taker and to take up and give out slack respectively in the in-throw and out-throw 85 of the loop-taker relatively to the fixed or rectilinearly reciprocating needle. This finger also serves to control the lead of the needle-thread between the loop-taker and the fabric as it is drawn up by the take-up.

The invention will be understood by reference to the accompanying drawings, in which—

Figure 1 is a sectional side elevation of a sewing machine embodying the present improvement, and Fig. 2 a plan view thereof taken from the lower side. Fig. 3 is an elevation of the stitch-forming mechanism and the loop-taker jogging means, looking toward the front end of the machine. Fig. 4 100 is an elevation upon an enlarged scale of the jogging loop-taker and its supporting and actuating means taken from the front end of the machine, and Fig. 5 a plan thereof, representing also the non-jogging looper. Fig. 6 is a side elevation, partly in section, of the jogging-looper supporting frame and the looper-driving pinions. Fig. 7 is an elevation, partly in section, of the needle-bar and a portion of the needle-jogging means, and 110 Fig. 8 a perspective view of the needle-jogging crank-rod and certain of its connec-

tions. Fig. 9 is a perspective view showing the fixed and jogging needle-holders and the adjacent portion of the needle-jogging mechanism, with certain of the parts detached from the others to expose the constructive features. Fig. 10 is a perspective view of the jogging needle-carrier detached. Fig. 11 is an under side view of the parts represented in Fig. 9, and Fig. 12 a similar view of a modification showing two needles mounted in the jogging needle-holder. Fig. 13 is a perspective view representing the under side of the throat-plate with its needle-guard and needles extending through the same. Figs. 14, 15 and 16 are plan views representing sections of the fabric with the marginal portions thereof covered respectively by straight-away and simple zigzag lines of stitches, straight-away and anchored zigzag lines of stitches and straight-away and double zigzag lines of stitches.

The frame of the machine is constructed with the bed-plate 1 and bracket-arm comprising the hollow standard 2 and the overhanging tubular member 3 terminating in the hollow head 4 formed at the top with the boss 5 affording the upper needle-bar bearing and at the bottom with the member 6 having the bushing 7 affording the lower needle-bar bearing, in which bearings are journaled the spaced upper and lower sections 8 and 9 of the tubular needle-bar. The adjacent end portions of the needle-bar sections are rigidly coupled together by means of a split collar 10 clamped thereon by screws 11 and formed in one side intermediate the ends with a deep notch 12 extending beyond the opposite side of the needle-bar, and carrying at the opposite side a lateral stud 13 embraced by the apertured lower end of the link 14 connected with the usual crank-pin 15 upon the take-up cam-cylinder 16 fixed upon the forward end of the rotary main-shaft 17. The cylinder 16 is provided with the cam-groove 16' entered by the roller-stud 18' upon the lateral arm 18 of the take-up arm 19 mounted upon the fixed fulcrum-stud 20.

As shown herein, the main-shaft 17 has fixed thereon the switch-cam 21 having the grooves 22 entered by the follower 23 pivotally mounted by means of the pin 24 upon the lower arm 25 of a rock-lever fulcrumed at 26 upon the arm 3 and having an upper arm 27 upon which is adjustably secured the shouldered stud 28 passing through the slot 27' of said arm and provided with the clamp-nut 29. The stud 28, which in practice is formed with a spherical extremity is embraced by one end of a link 30 whose apertured opposite end embraces the ball screw-stud 31 tapped into the laterally projecting boss 32 of the rocking frame 33 yoked to form the spaced members 34 and 35 embracing the bearing boss 5 and apertured

to fit the needle-bar section 8 upon which said yoke is journaled to swing.

The frame 33 is bored out to form a guideway 36 to receive the pin 37 which is secured by means of set-screws 38 within the apertured boss 39 of an arm 40 having a split hub 41 adjustably clamped by means of the screw 42 upon the upper portion of the oscillating crank-rod 43 which is journaled within the bore of the lower needle-bar section 9 and whose upper end portion is received in a bearing therefor afforded by the upper needle-bar section 8, as represented in Fig. 7, the arm 40 entering the slot 12 of the split coupling collar 10 between the adjacent ends of the needle-bar sections.

The rod 43 has fixed upon its lower end the crank 44 formed with a radial socket 44' entered by the sliding pin 45 having the transverse boss 46 apertured to form the eye 47 embracing a stud 48 carried by the rearwardly extending arm 49 of the needle-carrying slide-block 50 which is provided with the depending portion 51 having the usual needle-socket 52 in which is secured by means of the set-screw 53 the laterally jogging needle 54. The slide-block 50 is fitted within a transverse slideway 55 in the fixed needle-carrier 56 formed with the lateral slot 57 for the arm 49 of the slide-block 50 and having the depending part 58 with needle-socket 59 in which is secured by means of the set-screw 60 the fixed needle 61. As will be seen by reference more particularly to Figs. 3, 11, and 13, the needle 54 performs its lateral jogging movements in a plane rearward of the fixed needle 61. To facilitate the assembling of the parts, the arm 49 is provided with a shank portion entering a slot in the block 50 in which it is secured by means of the fastening screws 49', as represented in Fig. 10.

At its lower end, the lower needle-bar section 9 is formed with a hollow boss 62 formed with a lateral notch 63 to accommodate the lateral crank-arm 44 and having the oppositely extending members 64 to which the portion of the channel 55 above the slide-block 50 is fitted, and to which said carrier is secured by means of transverse screws 65 entering apertures 66' and 64' of said parts. As will be observed, the fixed needle 61 has a rectilinear path of movement corresponding with that of the needle-bar, while the jogging needle 54 has in addition to its endwise movement a lateral jogging movement communicated thereto through its connection with the oscillating rod 43 housed within the hollow needle-bar and having a sliding and pivotal connection with the rocking frame 33 which derives from the switch-cam 21 upon the main-shaft its rocking movements of one-half the frequency of the needle-bar reciprocations.

130

the under side of the bed-plate by means of the screws 67 passing through slots 68 therein, is the foot 69 of a bracket formed with a bearing boss 70 in which is journaled the 5 rotary loop-taker shaft 71 upon the upper end of which is fixed the loop-taker 72 formed with the loop-seizing beak 73 coöperating with the fixed needle 61 and having journaled therein the stationary thread-case 10 74 provided with the lateral finger 74' and containing the lower-thread bobbin 75.

Adjustably secured upon the seats 76 on the bottom of the bed-plate 1 by means of screws 77 passing through slots 78 therein 15 are the feet 79 of depending bracket members 80 formed with bearing bosses 81 to receive the alined fulcrum-pins 82, which are seated in transverse relation to the loop-taker shaft 87 and to the plane of lateral 20 movement of the jogging needle 54. The pins 82 are secured by means of set-screws 83 within spaced bosses 84 of a jogging frame 85 formed with an upwardly extending bearing member 86 in which is journaled 25 the loop-taker shaft 87 upon which is fixed the jogging loop-taker 88 which is provided with the beak 89 adapted for coöperation with the jogging needle 54 and having journaled therein the non-rotating thread-case 30 90 formed with the laterally extending finger 91 and containing the lower thread bobbin 92. The jogging frame 85 is formed with the divergently extending lateral arms 93 formed with the perforated bosses 94 in 35 which is secured by means of the set-screws 95 the slide-pin 96 disposed parallel with the fulcrum-pins 82, and entering a transverse aperture in the block 97 which has a second aperture fitted to the actuating eccentric 98, 40 as represented more particularly in Figs. 1 and 2.

Journalized in the depending bearing members 99 of the bed-plate is the horizontally disposed intermediate shaft 100 arranged in 45 transverse relation both to the loop-taker shafts and to the fulcrum of the jogging frame 85 and having fixed thereon by means of the set-screw 101 the bevel-pinion 102 meshing with the similar pinion 103 secured 50 upon the lower end of the loop-taker shaft 71, and having a second bevel-pinion 104 secured thereon by means of the set-screw 105 and meshing with a similar pinion 106 which is fixed upon the lower end of the 55 loop-taker shaft 87. The fulcrum-pins 82 are so disposed relative to the pinions 104 and 106 that their axis passes approximately through the intermeshing point of such pinions so as to permit the slight tilting 60 movement of the frame 85 without materially affecting the intermeshing relation of such pinions. As represented in the drawings, the part of the frame 85 intermediate the bosses 84 is cut out to afford clearance 65 for the pinions 104 and 106.

The intermediate shaft 100 has fixed upon its rearward end by means of the set-screw 107 the hub 108 of the pinion 109 which meshes with the gear-wheel 110 having its hub 111 secured by means of the set-screw 70 112 upon the lower shaft 113 which is formed with quartering cranks 114 connected by means of the pitmen 115 with the similarly arranged cranks 116 formed in the main or needle-driving shaft 17. As the 75 pinion 109 is one-half the size of the gear-wheel 110, and the bevel-pinions 102, 103, 104 and 106 are uniform in size, it will be observed that the loop-takers 72 and 88 derive from the main-shaft two complete rotations for each reciprocation of the needle-bar. 80

The eccentric 98 is secured upon the hub 117 of a gear-wheel 118 loosely mounted upon the intermediate shaft 100 and held 85 against lateral displacement thereon by means of the thrust-collar 119. Meshing with the gear-wheel 118 is the pinion 120 whose hub 121 is adjustably secured upon the shaft 113 by means of the set-screw 122 90 and serves to impart to the eccentric, through the gear-wheel 118, rotations at one-half the speed of the shaft 113 and the connected needle-bar actuating shaft 17.

By the means described, the loop-takers 95 72 and 88 are caused to perform uniform circular movements in which their excursions from an initial position, such as loop-seizing position, are performed with greater frequency than the lateral jogging movements of the needle 54 and the loop-taker support 86. The relation between the rotating means and the jogging means of the laterally movable loop-taker 88 is such that the coöperative relation of the loop-taker with 100 its respective needle is uniform regardless of their lateral positions. 105

It is evident that, not only must the loop-taker beak cross the needle-path just after the needle begins to rise for presentation of 110 its thread-loop thereto, but that the beak must move close to the needle, whatever the latter's lateral position, at the loop-seizing instant. Compensation for variations in the lateral position of the needle at 115 such time may be effected in either of two ways. The loop-taker may follow the needle-jogging movements in the amplitude of its lateral movement, in the customary manner, or a fixed period of uniform lateral 120 movement thereof may be advanced or delayed in timing so that any excess of such uniform maximum lateral movement may occur after the loop-seizing instant, the further and superfluous lateral movement of the 125 loop-taker being immaterial as regards the coöperation of the stitch-forming elements. In other words, so long as the loop-taker has the correct lateral position relatively to the needle at the loop-seizing instant, it is 130

wholly immaterial whether thereafter the loop-taker continue a lateral movement then in progress or immediately perform a retrograde movement. The second of the alternatives above described is that adopted in the present embodiment of this invention.

The compensative lateral loop-taker movements are effected in the present instance by resetting the pinion 120 upon its shaft 10 by temporarily loosening the set-screw 122 so as to advance or retract the loop-taker jogging cam 98 circularly for bringing the loop-taker laterally into operative relation with the needle when in loop-presenting position, but prematurely as regards its (the loop-taker's) further range of uniform lateral movement. It is, of course, unnecessary that the loop-taker should be laterally stationary, or at the point of reversal of its 15 lateral movements, during the loop-seizing action, so long as its continued lateral movement be not of such character as to cause injurious collision with the then rapidly rising needle. In the present mechanism, the loop-taker has so little bodily lateral movement and the needle performs its rising movement so rapidly relatively thereto, that there is no interference between these 20 stitch-forming elements.

It is obvious that the timing of coöperation of the loop-taker beak in one of its extreme lateral positions will be identical with the timing of such coöperation in the other extreme lateral position at the same distance from the neutral or straightaway stitching position which would correspond with an 25 adjustment of the needle-jogging connection 28 at the fulcrum point 26 of the rock-lever 25 27; any changes in the amplitude 30 of lateral movements of the needle insuring the descent of the needle alternately in extreme positions equi-distant from such neutral position, in the present machine. It is thus evident that adjustments of the loop-taker jogging mechanism to correspond with a given amplitude of lateral movements of 35 the needle will cause the loop-taker to coöperate with the needle exactly the same in each loop-presenting position thereof.

The bearing member 86 of the jogging loop-taker sustaining frame is provided with a lateral seat beneath the loop-taker upon which is secured by means of the fastening screw 123 the foot 124 of a holding 40 arm 125 extending upwardly and terminating in a member 125' formed in its lower face with the notch 126 to receive the laterally extending finger 91 of the thread-case 90, and adapted to restrain the latter against 45 rotary movement with the loop-taker 88.

The arm 125 is formed with a lateral lug 127 having a socket in which is secured by means of the set-screw 128 the shank of the thread-controlling finger 129 which is disposed substantially upon a level with the 50

65

top of the loop-taker and intermediate the latter and the path of reciprocation of the jogging needle 54. In order to prevent the escape of the thread which it controls, the finger 129 has a lateral extension 130 at its 70 extremity.

Secured upon the bed-plate is the throat-plate 131, constituting the work-support which is formed with the usual feed-dog apertures 132 and the needle-apertures 133 and 134, the former being in the form of a transverse slot to accommodate the jogging needle 54. Secured upon a seat intermediate the feed-dog apertures by means of screws 135 is the needle-guard 136 formed with the usual oppositely facing grooves 137 to receive the respective needles and to insure the throwing out of their thread-loops wholly upon the sides occupied by their respective loop-takers. The throat-plate is shown provided at one edge with depending spaced holding lugs 138 embracing the lateral finger 74' of the thread-case 74 to restrain it against rotation with its sustaining loop-taker 72.

The machine is shown provided with the presser-bar 139 to which is secured the shank of the presser-foot 140 opposed to the feed-dog 141 having feed points extending through the throat-plate apertures 132 and sustained by the feed-bar 142 connected with and deriving operative feeding movements from the rock-shaft 143 which receives its rocking movements from the actuating eccentric 144 through suitable connections, the feed-bar deriving its rising and falling movements from the rock-shaft 145 which receives its rocking movements from the feed-lift eccentric 146.

In the use of the machine, the loop-taker 72 coöperates with the fixed needle 61 in the production of a straight seam and the loop-taker 88 follows the lateral movements of the jogging needle 54 in the production of a zigzag seam. In the ordinary adjustment of the parts, the overlapped marginal portions of the sole *a* and upper *b* of the tabi are stitched together by the line of straightaway stitching *c* and the raw edges are bound by means of the line of zigzag stitching *d* in which the in-throw punctures of the jogging needle 54 are in substantial alinement with the straight row of punctures of the fixed needle 61, as represented in Fig. 14. When the machine is used in connection with loose-textured fabrics requiring a more secure anchorage for the binding overseam *d*, the position of the in-throw punctures of the jogging needle may be arranged beyond the straight-away seam *c* by slightly shifting the jogging cam 21 upon the main-shaft 17 or adjusting the arm 40 upon the crank-rod 43; or side-pointed needles, as represented in Fig. 13, may be employed with their points set op-

positely, and that of the jogging needle arranged in the direction of the in-throw, so that the threads of the straight-away and over-edge seams will be crossed, as represented in Fig. 15.

To provide for more effectively covering the raw edges of the work, the slide-block 50 may be constructed to hold two needles arranged in the line of feed. As represented in Fig. 12, the extension 51 of the block has a socket 147 against one wall of which are clamped the shanks of two needles 54 and 54' by means of the channeled block 148 with convergently inclined walls engaging the needle-shanks and pressed against the same by means of the clamp-screw 53. With the needle-carrying slide-block 50 thus constructed and equipped, a double-zigzag overseam may be produced with the seams *d* and *d'* overlapped upon the upper face of the work and which may be anchored or not, as may be desired, in the straight-away seam *c*, as represented in Fig. 16.

From the foregoing description, it will be evident that the present improvement is not limited to the specific embodiment herein shown and described, but may be very materially modified in the construction and arrangement of its parts within the scope of the invention.

Having thus set forth the nature of the invention what I claim herein is:—

1. In a sewing machine, in combination, a needle, means for imparting thereto endwise reciprocations, and means for imparting to the needle lateral jogging movements of less frequency than its reciprocating movements, a circularly moving loop-taker coöperating with said needle, means independent of the needle-jogging means for imparting to said loop-taker bodily jogging movements transversely of its axis of circular movement and correspondingly in amplitude with the lateral movements of the needle, and means acting upon the loop-taker independently of its jogging means and of the lateral movements communicated by it to the loop-taker for imparting thereto circular movements adapted to insure uniform coöperative relation between the loop-taker and needle in laterally different loop-presenting positions of the latter.

2. In a sewing machine, the combination with a rectilinearly reciprocating needle confined to straight-away stitching and an endwise reciprocating and laterally jogging needle, of a circularly moving loop-taker coöperating with said rectilinearly reciprocating needle, a second circularly moving loop-taker coöperating with the laterally jogging needle, means for imparting lateral movements to the second-named loop-taker transversely to its axis of movement and correspondingly with the lateral movements of said needle, and means including a shaft

carrying independent actuating members with which said loop-takers are respectively connected and from which they derive operative movements.

3. In a sewing machine, the combination with an endwise reciprocating and laterally jogging needle and an actuating shaft therefor, of a loop-taker shaft mounted independently of said actuating shaft, a loop-taker mounted thereon, a fulcrum upon which said loop-taker shaft is adapted to vibrate in the direction of the lateral jogging movements of said needle, means connected to said shaft substantially at its fulcrum point for imparting operative movements to said loop-taker, and means for imparting lateral jogging movements to said shaft.

4. In a sewing machine, the combination with an endwise reciprocating and laterally jogging needle, of a loop-taker shaft, a loop-taker mounted thereon, a fulcrum upon which said loop-taker shaft is adapted to vibrate in the direction of the lateral jogging movements of said needle, an actuating shaft mounted in fixed bearings, intermeshing gears mounted respectively upon said actuating shaft and said loop-taker shaft and having their intermeshing point upon substantially the axis of said fulcrum, and means for imparting lateral jogging movements to said loop-taker shaft.

5. In a sewing machine, the combination with an endwise reciprocating and laterally jogging needle, of a loop-taker shaft, a loop-taker mounted thereon, a fulcrum disposed transverse to said loop-taker shaft upon which the latter is adapted to vibrate in the direction of the lateral jogging movements of said needle, an actuating shaft mounted in fixed bearings and disposed transverse to said loop-taker shaft and to its fulcrum, intermeshing bevel-gears mounted respectively upon said actuating shaft and the loop-taker shaft and having their intermeshing point upon substantially the axis of said fulcrum, and means for imparting lateral jogging movements to said loop-taker shaft.

6. In a sewing machine, the combination with a rectilinearly reciprocating needle and an endwise reciprocating and laterally jogging needle, of a circularly moving loop-taker coöperating with said rectilinearly reciprocating needle, a shaft upon which said loop-taker is mounted, a second circularly moving loop-taker coöperating with the laterally jogging needle, a laterally jogging shaft upon which the second loop-taker is mounted, a fulcrum disposed transverse to and sustaining said laterally jogging loop-taker shaft, an actuating shaft mounted in fixed bearings and disposed transverse to said loop-taker shafts and to said fulcrum, a pair of intermeshing bevel-gears mounted respectively upon said actuating shaft and the first-mentioned loop-taker shaft, a sec-

ond pair of intermeshing bevel-gears mounted respectively upon said actuating shaft and said jogging loop-taker shaft and having their intermeshing point upon substantially the axis of said fulcrum, and means for imparting lateral jogging movements to the second-named loop-taker shaft upon said fulcrum.

7. In a sewing machine, the combination 10 with an endwise reciprocating and laterally jogging needle, of a loop-taker shaft, a loop-taker mounted thereon, a jogging frame provided with a bearing for said loop-taker shaft and with a lateral arm, a fulcrum-pin 15 transverse to said shaft upon which said frame is mounted, an actuating shaft, intermeshing gears mounted respectively upon said actuating shaft and said loop-taker shaft and having their intermeshing point 20 in substantial alinement with said fulcrum, an eccentric, actuating means therefor, and a connection between said eccentric and the lateral arm of said jogging frame for imparting lateral jogging movements to the 25 loop-taker corresponding with those of the needle.

8. In a sewing machine, the combination 30 with an endwise reciprocating and laterally jogging needle, of a loop-taker shaft, a loop-taker mounted thereon, a jogging frame provided with a bearing for said loop-taker shaft and with a lateral arm, a fulcrum-pin 35 transverse to said shaft upon which said frame is mounted, an actuating shaft, intermeshing gears fixed respectively upon said actuating shaft and said loop-taker shaft and having their intermeshing point in substantial alinement with said fulcrum, an eccentric loosely mounted upon said shaft, a connection between said eccentric and the lateral arm of said jogging frame for imparting lateral jogging movements of the 40 loop-taker corresponding with those of the needle, and independent driving means for 45 rotating said actuating shaft and eccentric at different speeds.

9. In a sewing machine, the combination 50 with an endwise reciprocating and laterally jogging needle, of a coöperating loop-taker, a jogging frame provided with a lateral arm and adapted to sustain said loop-taker and to impart thereto jogging movements corresponding with those of the needle, a fulcrum 55 for said frame, a rotating eccentric, a block mounted thereon and formed with an aperture to embrace the same and with an aperture transverse thereto, and a pin entering the transverse aperture of said block and connected with the lateral arm of said frame whereby the latter derives its jogging movements from said eccentric.

10. In a sewing machine, the combination 60 with an endwise reciprocating and laterally jogging needle, jogging means therefor, and adjusting means for varying the amplitude 65

of the needle-jogging movements, of a loop-taker mounted for circular movement, means for imparting bodily jogging movements to said loop-taker in the direction of the corresponding movements of said needle, means 70 for imparting to said loop-taker its operative circular movements, and means for varying the loop-seizing position of the loop-taker beak relatively to the jogging movements of the loop-taker.

11. In a sewing machine, the combination 75 with an endwise reciprocating and laterally jogging needle, jogging means therefor, and adjusting means for varying the amplitude 80 of the needle-jogging movements, of a rotary loop-taker, a shaft upon which the same is mounted, a jogging frame in which said shaft is journaled, a support on which said frame is movably mounted, an actuating shaft, intermeshing gears fixed respectively 85 upon said actuating shaft and said loop-taker shaft, an eccentric with means for rotating the same at a slower speed than but in fixed proportion to that of said actuating shaft, an operative connection between said eccentric and said jogging frame, and means 90 whereby the relative timing of said actuating shaft and the eccentric may be varied without changing their proportional speeds of rotation.

12. In a sewing machine, in combination, 95 a work-support, a circularly moving loop-taker, a support therefor movable relatively to said frame, means for imparting to the loop-taker support lateral jogging movements relatively to said work-support and transversely to the axis of circular movement of the loop-taker, and means acting upon the loop-taker independently of said jogging means and of the lateral movements communicated by it to the loop-taker for imparting thereto circular movements comprising excursions from an initial position of greater frequency than said jogging movements.

13. In a sewing machine, in combination, 100 a frame, a circularly moving loop-taker, a thread-case journaled therein, a support movable relatively to said frame upon which said loop-taker is mounted to perform its 105 circular movements, means for imparting to the loop-taker uniform circular movements for consecutive stitches, means sustained by said support for restraining the thread-case against circular movement with 110 the loop-taker, and means connected with said support for imparting to it lateral jogging movements transverse to the axis of circular movement of the loop-taker.

14. In a sewing machine, the combination 115 with an endwise reciprocating and laterally jogging needle, and an actuating shaft mounted in fixed bearings and from which 120 said needle derives operative movements, of a circularly moving loop-taker having a 130

thread-case journaled therein, a loop-taker support adapted to perform jogging movements relatively to said shaft, actuating means adapted to impart to said loop-taker 5 uniform circular movements for consecutive stitches, means for imparting lateral jogging movements to said support, and a holding element carried by the loop-taker support and adapted to engage said thread-case for restraining the same against circular movement with the loop-taker.

15. In a sewing machine, the combination with an endwise reciprocating and laterally jogging needle, of a circularly moving loop-taker, actuating means for imparting circular movements to said loop-taker, means for imparting to said loop-taker lateral jogging movements transverse to the axis of its circular movements, and a thread-controlling element occupying a position intermediate said needle and loop-taker.

20 16. In a sewing machine, the combination with an endwise reciprocating and laterally jogging needle, of a circularly moving loop-taker, a laterally movable support for said loop-taker, actuating means for imparting circular movements to said loop-taker, means connected with said support for imparting to said loop-taker lateral jogging 25 movements transverse to the axis of its circular movements, and a thread-controlling finger fixed upon said support and occupying a position intermediate said needle and loop-taker.

30 17. In a sewing machine, the combination with an endwise reciprocating and laterally jogging needle, of a circularly moving loop-taker, a thread-case journaled therein, a support upon which said loop-taker is mounted for effecting its circular movements, means for imparting said movements to the loop-taker, means connected with said support for imparting to it lateral jogging movements, a holding element carried by 35 said support and adapted to engage said thread-case for restraining it against circular movement with the loop-taker, and a thread-controlling finger sustained by said holding element and occupying a position intermediate said needle and loop-taker.

40 18. In a sewing machine, the combination with a reciprocating tubular needle-bar, of a needle mounted thereon and laterally movable relatively thereto, means including a connection extending through said needle-bar for imparting lateral jogging movements to said needle, and loop-taking means coöperating with said needle.

45 19. In a sewing machine, the combination with a reciprocating tubular needle-bar fixed against rotation, of a laterally movable needle mounted thereon, a rocking frame fulcrumed concentrically with said needle-bar, means for rocking said frame, a crank-rod within said needle-bar and carrying a

crank having a connection with said needle, an operative direct connection between said crank-rod and said rocking frame, and loop-taking means coöperating with said needle.

20. In a sewing machine, the combination with a reciprocating tubular needle-bar and a fixed bearing in which the same is journaled, of a laterally movable needle mounted thereon, a rocking frame yoked to embrace said bearing and journaled at opposite sides thereof concentrically with said needle-bar, means for rocking said frame, a crank-rod within said needle-bar and carrying a crank having a connection with said needle, means directly connecting said crank-rod and said rocking frame, and loop-taking means coöperating with said needle.

25 21. In a sewing machine, the combination with a reciprocating tubular needle-bar and a fixed bearing in which the same is journaled, of a laterally movable needle mounted thereon, a rocking frame yoked to embrace said bearing and journaled at opposite sides thereof concentrically with said needle-bar and provided with a guideway parallel with the latter, means for rocking said frame, a crank-rod within said needle-bar and carrying a crank having a connection with said needle, a direct operative connection between said crank-rod and said rocking frame, a lateral arm rigidly secured upon said crank-rod and carrying a guide-pin adapted to enter the guideway of said rocking frame, and loop-taking means coöperating 30 with said needle.

35 22. In a sewing machine, the combination with a reciprocating tubular needle-bar provided with a transverse slideway, of a carrier fitted to and movable within said slideway, a needle mounted in said carrier, a rod fitted within said needle-bar and carrying a crank-arm extending laterally therefrom, an operative connection between said crank-arm and said carrier, means for oscillating said rod to impart lateral jogging movements to said needle, and loop-taking means coöperating with said needle.

40 23. In a sewing machine, the combination with a reciprocating tubular needle-bar provided with a transverse slideway, of a carrier fitted to and movable within said slideway and provided with a lateral arm carrying a stud, a needle mounted in said carrier, a rod fitted within said needle-bar, a lateral crank-arm fixed upon said rod and provided with a radial socket, a slide-pin fitted within the crank-arm socket and formed with an eye embracing the stud upon the lateral arm of said carrier, means for oscillating said rod to impart lateral jogging movements to said needle, and loop-taking means coöperating with said needle.

45 24. In a sewing machine, the combination with a reciprocating tubular needle-bar

- formed in separate alined sections, of a laterally movable needle mounted upon one of said sections thereof, a rod journaled within the needle-carrying needle-bar section and 5 having a bearing in the other needle-bar section, an operative connection between said rod and the needle through which lateral jogging movements are imparted to the latter, a lateral arm fixed upon said rod intermediate the adjacent ends of the needle-bar sections, means applied to said arm external to the needle-bar for imparting oscillatory movements to said rod, and loop-taking means coöperating with said needle.
- 15 25. In a sewing machine, the combination with a tubular needle-bar formed in separate alined sections, a collar provided on one side with a lateral stud and in the opposite side intermediate its ends with a lateral notch and affording a rigid coupling between the spaced adjacent ends of said needle-bar, and means connected with said lateral stud for imparting rectilinear reciprocating movements to said needle-bar, of a 20 laterally movable needle mounted upon one of the sections of said needle-bar, a rod journaled within the needle-carrying needle-bar section and having a bearing in the other needle-bar section, an operative connection 25 between said rod and the needle through which lateral jogging movements are imparted to the latter, a lateral arm fixed upon said rod and emerging therefrom through the lateral notch of said collar, means applied to said arm for imparting oscillatory movements to said rod, and loop-taking means coöperating with said needle.
- 30 26. In a sewing machine, in combination, a rectilinearly reciprocating needle-bar, a 40 needle fixed thereon, a laterally movable needle mounted thereon, means for imparting to the second-named needle lateral jogging movements relatively to the first-named needle, loop-taking devices coöperating with 45 said needles in the production of stitches, and means for imparting to the one of said loop-takers coöperating with the laterally movable needle lateral jogging movements corresponding with the lateral movements of 50 said needle.
- 55 27. In a sewing machine, in combination, a rectilinearly reciprocating needle fixed against lateral movement, an endwise reciprocating and laterally movable needle, feeding mechanism, means for imparting to the second-named needle lateral jogging movements between points respectively in alinement with the first-named needle relatively to the direction of feed and at one side thereof, and loop-taking devices coöperating with 60 said needles, one of said devices being adapt-
- ed to follow the movements of said laterally moving needle.
28. In a sewing machine, in combination, a reciprocating needle-bar, means for restraining it against turning, a needle fixed thereon against lateral movement, a second and laterally movable needle mounted upon said needle-bar, means for imparting to the second-named needle lateral jogging movements between extreme positions at opposite sides of the first-named needle, and loop-taking devices coöperating with said needles. 65
- 70 29. In a sewing machine, the combination with the feeding mechanism, of stitch-forming mechanism comprising a rectilinearly reciprocating needle-bar, a needle fixed thereon, a needle carried thereby and movable thereon transversely of the direction of feed and in a plane at one side of the fixed needle, 75 jogging means for the laterally movable needle, and loop-taking devices coöperating with said needles.
- 80 30. In a sewing machine, the combination with the feeding mechanism, of stitch-forming mechanism comprising a rectilinearly reciprocating needle-bar, a needle mounted thereon and fixed against lateral movement, a reciprocating carrier moving with said needle-bar and adapted for lateral movement transverse to the direction of feed, a plurality of needles mounted in said carrier and arranged in a plane parallel with the direction of feed, means for imparting to said carrier lateral jogging movements, and loop-taking devices coöperating with said needles. 85
- 90 31. In a sewing machine, the combination with the feeding mechanism, of stitch-forming mechanism comprising a rectilinearly reciprocating needle-bar, a needle fixed thereon, a carrier mounted upon said needle-bar and movable thereon transversely to the direction of feed, a plurality of needles mounted in said carrier and arranged in a plane parallel with the direction of feed, means for imparting to said carrier lateral jogging movements, a loop-taker coöperating with said fixed needle and adapted to perform consecutive loop-seizing operations in the same position, and a loop-taker coöperating 95 with the laterally jogging needles and adapted to perform consecutive loop-seizing operations in different positions corresponding with the lateral positions of said needles. 100
- 105 In testimony whereof, I have signed my name to this specification, in the presence of two subscribing witnesses.

ALBERT H. DE VOE.
